UNITED STATES PATENT OFFICE

92,970

DESIGN FOR AN ENVELOPE MOISTENER

Charles G. MacDermed, Denver, Colo.

Application May 21, 1934, Serial No. 51,870

Term of patent 7 years

To all whom it may concern:

Be it known that I, CHARLES G. MACDERMED, a citizen of the United States of America, residing at Denver, in the county of Denver and State of Colorado, have invented a new, original, and ornamental Design for Envelope Moisteners, of which the following is a specification, reference being had to the accompanying drawing, forming part hereof.

The figure is a perspective view of an envelope moistener showing my new design.

I claim:

The ornamental design for an envelope moistener as shown.

CHARLES G. MACDERMED.
